DUAL SERVICE HEATING SYSTEM

Oscar G. Watt, Tulsa, Okla.

Application June 26, 1939, Serial No. 281,281

8 Claims. (Cl. 237—19)

This invention relates to an improved method and apparatus for a heating system, and more particularly, but not by way of limitation, to a double or dual service domestic hot water supply and house heating system. The present application is a continuation-in-part of my application Serial No. 216,349, filed June 28, 1938.

In many sections of the country where gas and individual heaters are employed for home heating purposes, the rooms of the home are usually heated by small gas heaters having an open flame. Many disadvantages are incident to this type of heating, in that the gas flame is subject to the possibility of being blown out by normal circulation of room air, thus endangering the house and its occupants to the hazard of a fire or explosion, or asphyxiation from gas or carbon monoxide gas fumes. Furthermore, in many sections of the country where natural gas is not abundant, but due to warm climatic conditions, a costly and bulky heating plant is not necessary. And more specifically, in any climate, at certain times of the year such as early spring and late fall, it is desirous to heat certain rooms of the house such as a bathroom or dressing rooms yet the weather is not cold enough to warrant the operation of the individual house heating plant. Also at night after the house heating plant is shut down, a warm bathroom is often desired.

Furthermore, it has been found that in closed gravity heating systems heretofore known, utilizing the domestic hot water supply, such as those disclosed in the patents to Cowles et al., No. 835,812 and Thompson No. 1,240,101, the system can be utilized for supplying either the domestic hot water to the plumbing fixtures or the heating units individually, but none of these systems provide a single circulating system capable of a dual service for simultaneously supplying both the heating units and domestic hot water to a faucet, wherein both services can be utilized at exactly the same time without one service interfering with the other.

It is therefore an important object of this invention to provide a heating system for home or building heating utilizing the domestic hot water circulating system and equipment supplying the various plumbing fixtures throughout the house for simultaneously supplying hot water to radiators for heating purposes.

And still another object of the invention is to provide a home heating system that is healthful in that it does not burn up the oxygen in the room air and is maintained at such a con-

stant temperature with clean dry air so as not to cause deterioration of interior decorations of the room or cause sweating of walls and windows.

And still another important object of this invention is to provide a dual service hot water supply and heating system for homes in which circulation is propelled by the natural law of gravity and is capable of being kept free of air by regular use of the hot water faucets, and can be either automatically or manually controlled.

And still another object of this invention is to provide a home heating system of closed hot water gravity circulation type employing the same equipment for the heating radiators that is utilized for supplying hot water for the various plumbing fixtures of the home, a system that supplies heat to the various rooms of a home any time there is hot water for the plumbing fixtures, said system being independent of any auxiliary or additional home heating plant.

And still another object of this invention is to provide a closed system of home heating by high pressure hot water radiators that has eliminated most of the conventional equipment such as expansion tanks, pressure reducing valves, gauges, pumps, and the like.

And still another object of this invention is to provide a home heating system of the closed hot water circulating type that is simple in design and construction in that it needs less attention for operation, economical and durable in that there is less equipment to purchase, keep in repair and depreciate.

And still another important object of this invention is to provide a single hot water circulating system that will perform a dual service of supplying circulating hot water to within a few inches of the faucet of a plumbing fixture of a dwelling, as well as supplying hot water to high pressure radiators as a medium for room heating purposes, said services capable of being rendered simultaneously without one service interfering with the other.

And still an additional object of this invention is to provide a single system of closed hot water circulation that will perform a dual service of supplying circulating hot water to within a few inches of the plumbing fixture of a dwelling, as well as supplying hot water to radiators as a medium for air heating purposes, said circulating system so constructed as to maintain constant circulation and to exhaust any air in the system or radiators through the regular use of a hot water faucet of a plumbing fixture, although the faucet may be located at a lower

elevation than the radiator, or at some remote point in the piping system.

Another object is to provide a heating system wherein the same kind of fuel is used to heat the small bathroom, dressing room or efficiency apartment that is used for heating the domestic hot water.

Another object is to provide a system of hot water circulation that will maintain complete and uninterrupted circulation of all water contained in the hot water pipes between the tank and the plumbing fixture faucet, thus delivering hot water instantly upon opening the faucet without the necessity of having to draw any cold water that may have been standing in the pipes between the tank and faucets, this circulation to continue, although some point in the circulating line has been raised to a higher elevation than the faucet.

Other objects and advantages of the invention will be evident from the following detailed description read in conjunction with the accompanying drawings which illustrate one form of my invention.

In the drawings:

Fig. 1 is a view in broken elevation of the improved dual service system of hot water circulation for domestic hot water supply and room heating, with portions of the structure in which it is installed in section.

Fig. 2 is a detail view in front elevation showing the arrangement of one of the heating units with a plumbing fixture and more particularly showing the two-way or transfer valve for controlling the supply and return of circulating hot water.

Fig. 3 is a top plan view of Fig. 2.

Fig. 4 is a detail view of a portion of the supply line in the circulating system.

Referring now to the drawings wherein corresponding parts are designated by like numerals of reference, and more particularly to Fig. 1, reference character 2 indicates a hot water boiler or tank usually disposed in the basement 4 of a home, however, it will be apparent that any arrangement or location of the hot water tank 2 can be made according to the construction of the building or home with which it is to be utilized.

A city water line 6 communicates with the city water main (not shown) and the hot water tank 2 for supplying cold water at city main pressure, which in most instances varies from 25 to 100 pounds per square inch. A valve 8 is interposed in the line 6 which in open position allows water to flow through line 6 where it is discharged into the tank 2 at a point adjacent to the bottom of the tank. The inflow of cold water continues until the pressure in tank 2 and of the pipes of the system to be hereinafter referred to, equals the city main pressure, thereby producing a high pressure system capable of a high velocity flow.

Water discharged in tank 2 may be heated by various means, but the present invention discloses a conventional gas fired heater 10 arranged adjacent to tank 2, and communicating therewith by pipes 11 and 106. With the heater 10 heating the water in tank 2, the water is expanded and causes circulation throughout the system. A thermostat 9 is provided in tank 2 for controlling the temperature of the water in the tank. A hot water supply pipe 12 extends from the top of the tank 2 through floor 14 of the building into communication with a two-way or transfer valve 16 disposed in the wall or partition 17. An auxiliary hot water supply pipe 18 extends from the top orifice of the valve 16 into communication with

a hot water faucet 20 of a lavatory 22. A by-pass line 24 extends from a side orifice of the valve 16 into communication with a downwardly extending return line 25 discharging into the tank 2 at a point adjacent to the bottom thereof.

From the foregoing, it will be apparent that with the valve 16 set in proper position, hot water will circulate by gravity from the top of tank 2 up through the supply pipe 12, to the two-way valve 16 and back through the by-pass line 24 and the return line 25 to the bottom of tank 2, as long as there is a difference in the temperature of the water in the pipes 12 and 25, and the system is free of air.

In a closed system (closed to atmosphere) as at the present invention, any air that may be present in the system will be eliminated by opening the lavatory faucet 20 wherein air will be forced from the tank up through the pipe 12 and exhausted out through faucet 20 to provide a system which will remain free of air by the regular use of the fixture faucets.

In order to utilize this single system of closed domestic circulating hot water supply as a means for heating the various rooms of a house, building or the like, and thus perform a dual service, it is only necessary that a heating means such as hot water high pressure radiators be added. It is to be understood that the transfer valve 16 is installed in the supply line 12 at a point at least as high as the top of a radiator 26. In this arrangement (as clearly shown in Figs. 2 and 3), an auxiliary hot water supply line 28 extends from the valve 16 into communication with the top of the radiator 26. A return line 30 extends from the bottom of the radiator 26 into communication with the return line 25 for the tank 2. The valve 16 may be any conventional type of two-way transfer valve, however, it is preferable to use a double-seating valve having four orifice openings for receiving pipe connections 12, 18, 24 and 28. Any rotation of the valve handle 32 (projecting from the wall) does not affect flow of fluid from supply pipe 12 to supply pipe 18 and there will always be circulation to the lavatory faucet 20 regardless of the position of the valve. However, it will be apparent that the valve can be rotated to allow discharge of hot water into the pipe 28 for supplying hot water as a heating medium to the radiator 26, simultaneous with the flow of hot water into the pipe 18. With the valve 16 manipulated to supply a heating medium, circulation of the hot water is from the pipe 12 through the valve 16, pipe 28, radiator 26, pipe 30, and back to the return line 25 and the tank 2, it being understood that with the valve in this position, return circulation through line 24 is closed. With the valve rotated to cut off the supply to line 28, return circulation from the faucet 20 is through lines 24 and 25, therefore assuring that with the valve set in one extreme position or the other, return circulation to the tank can only be one way, i. e., either through lines 24 and 25, or through radiator 26 and line 30 to line 25, thus preventing the possibility of a short circuit in the circulation of the water. It will likewise be apparent that with any partial rotation of the valve, fluid can circulate simultaneously through the line 24 and the radiator 26. In this manner, the valve can be regulated to determine the supply of circulating hot water to the radiator, whether in whole or in part. This adjustable feature provides selective control of the heating medium supplied to the

radiator, which can be varied according to climatic conditions.

The foregoing description has only been concerned with the supply of a heating medium to the radiator 26 for one room of a dwelling, particularly to a bathroom having a lavatory. The present invention discloses the radiator disposed beneath the lavatory, but it will be apparent that the radiator can be disposed anywhere in the room as long as the proper communication is provided between the supply and return lines, and the faucet. However, in order to supply hot water to a radiator or radiators arranged in a plurality of rooms in the dwelling, it is only necessary to provide auxiliary or branch extensions from the main supply line 12 and return line 25.

It will be apparent that with a hot water circulating system of this type that numerous radiators can be located adjacent and below plumbing fixtures supplied with hot water, and many arrangements can be made according to the arrangement of the dwelling. However, for purposes of illustration, the present invention discloses only one arrangement, wherein a T-connection 34 is provided in line 12 and communicates with the auxiliary supply line 36 supplying hot water to a radiator 38. The radiator 38 is shown disposed in any conventional fixture 40, such as a dressing table, cabinet, or the like, however the radiator may be separately arranged in a room. A control valve 42 is interposed in the line 36 controlling the flow of hot water to the radiator 38. An auxiliary return line 44 extends from the bottom of the radiator 38 into communication with a connection 46 in the main return line 25. It will be apparent that any air in the supply line 38 can be exhausted through the hot water faucet 20.

A second auxiliary supply line 48 extends from T-connection 50 and is provided with auxiliary or branch lines 52 and 54 extending therefrom. It will be obvious that the supply line 48 can have as many extensions as are practical, depending upon the number of radiators disposed in the various rooms of the building. In the present disclosure, line 48 is plugged at 57 but may be extended if desired. A line 55 extends from a T-connection 56 in line 54 into communication with a control valve 58 controlling discharge of hot water to radiator 60. With the valve 58 in open position, hot water is discharged into the radiator 60 for supplying a heating medium thereto. A return line 62 provides communication from the bottom of the radiator 60 to an auxiliary return line 64 communicating with the main return line 25. Line 64 can have as many extensions as desired. Hot water flowing in line 52 passes into pipes 66, 68 and 70 and into communication with a T-fitting 72, where an auxiliary line 74 provides communication with a hot water faucet 76 of a plumbing fixture 78. Line 70 extends downwardly from the T-fitting 72 into communication with a hot water faucet 86 of a laundry tub or fixture 88. A line 90 provides a connection between faucet 86 and a T-fitting 92 communicating with the tank 2 to complete the circuit. It will be apparent that the line 90 acts as a return line.

Alluding further to the radiator 60, it will be noted that it is disposed in a remote position from the plumbing fixture, and in order to relieve air from the radiator 60 and its supply pipe 54, a line 88 (preferably a small metallic tube) extends from the high point of a T-fitting 56, 75

and pitches upward into communication with T-fitting 82, communicating with pipe 88 through a bushing 84 and jet nipple 87. Any air in the radiator 60 and pipe 88 will be discharged through pipes 88 and 66, and faucet 76, as will be hereinafter described.

Referring now to the sink 78 and laundry tub 88, it will be noted that they are located at a point which makes it necessary or desirable to place some part of the circulating pipes at a point higher than the faucets of these fixtures, thus creating a place in the system for the accumulation of air at the highest elevation of the pipes. Normally, an air pocket would not prevent water from being drawn from a faucet of the fixture, however, such an air pocket would prevent gravity circulation through the system when the faucets were closed. The manner of installing the auxiliary circulating pipes so as to provide constant circulation, and likewise prevent any possible accumulation of air in such sufficient quantity to prevent circulation will now be explained.

The faucet 76 is in communication with the top and bottom of tank 2 through pipes 12, 48, 52, 66, 68, 70, 98 and 25, thus providing a complete circulation of hot water to and from the tank. A check valve 104 is provided to prevent a backward flow when faucet 76 is opened. It will be noted that most of the supply lines feeding the quick opening faucet 76 are of higher disposition than the faucet. In order to safeguard against a possible air lock in the auxiliary supply lines 52 and 70, two horizontally connecting lines 66 and 68 are arranged in floor 93 providing communication between lines 52 and 70. By properly sizing the pipes 66 and 68 in relation to the delivery capacity of pipe 10 and faucet 76, a sufficiently high velocity of water can be had through these pipes to force out all air in the pipes upon opening the faucet. In a closed system, high pressure water pipes do not accumulate much air once they are freed of air. The use of two smaller connecting pipes 66 and 68 instead of one horizontal pipe of the same capacity as pipe 70, divides the horizontal flow of hot water into two channels, or conduits, with one conduit located at a higher level than the other, so that the higher conduit 66 will serve as a container of air for any period of time when the faucet 76 is not being used, while the lower pipe 68 continues to act as a circulating pipe for hot water by constantly maintaining a water filled circuit. It has been found in practice that a very small circulating pipe will pass enough water (even at a low velocity) to keep all supply lines sufficiently hot, although the total carrying capacity of the supply lines is much greater than the capacity of one small circulating pipe.

Referring to Fig. 4, it is to be noted that the arrangement of pipes 66 and 68 is such that there will be a greater fluid flow, and at a higher velocity, through pipe 66 than through pipe 68 when faucet 76 is open. This is accomplished by connecting pipe 66 directly into the top of auxiliary supply pipes 52 and 70, thereby requiring only two right angle turns between the upward flow in 52, and the downward flow in 70. The pipe 68 is interposed between the pipes 52 and 70 by the T-fittings 92, 94, elbows 96 and 98, thus creating more friction due to the increased number of turns. In the present instance, four turns are necessary for pipe 68, as compared with two for pipe 66. Water flowing through supply line 52 at a high velocity will have a tendency to flow in a straight line through T-fitting 92 and on to

fitting 69, due to the increased frictional resistance of the T-fitting 92 and elbow 96.

Alluding further to the pipe 88 for exhausting air from radiator 60 and supply line 54, the pipe 88 contains in addition to the air to be exhausted, water at city main pressure, and will therefore discharge a small amount of water through the jet nipple 67 and bushing 81 into the pipe 66 each time the faucet 76 is opened. The jet 67 increases the velocity of water flowing from pipes 52 and 80 into pipe 66, in order to assist in exhausting any air accumulation at the high point of the system. It will be apparent that any number of radiators can have air exhausted by means of an exhaust line similar to pipe 88 connected to a jet nipple as shown in Fig. 4. It will thus be obvious that with the pipe 66 serving as a container for air, the high velocity through 66 created by the jet 67, as well as the T-fitting 69, quickly exhausts any air in pipe 66 upon opening the faucet 76. However, it is understood that pipe 68 has sufficient capacity to provide ample circulation of hot water to faucet 76, and the foregoing arrangement assures a constant circulation to faucet 76, as well as means for relieving any air in the system. It will be obvious that faucet 86 can likewise be utilized to free the system of air.

The expansion of water in tank 2 when heated is provided for by the regular use of the hot water throughout the system. However, if no water is drawn from the faucets during the time the water in the tank is being heated, the expansion is received by the city water main as long as the valve 8 is open. In case the valve 8 should be closed during the time water is being heated, and no water is drawn from faucets, the line 6 is provided with a safety valve 102 for relieving any excess pressure due to expansion. The pipe 106 is provided with a drain valve 108.

From the foregoing, it will be apparent that the invention provides a single system of hot water circulation capable of performing the dual service of simultaneously supplying hot water to plumbing fixtures and hot water radiators of a dwelling without one service interfering with the other. While the present invention only discloses three radiators, it will be apparent that the system can be extended for supplying as many radiators as is necessary, even though the radiators be located remote from, adjacent to, above or below a plumbing fixture whose hot water faucet is used to relieve the system of air locks. The fixtures and radiators may be supplied by either a basement up-feed supply line, or an overhead down-feed supply line.

Changes may be made in the combination and arrangement of parts as heretofore set forth in the specifications and shown in the drawings, it being understood that any modification in the precise embodiment of the invention may be made within the scope of the following claims without departing from the spirit of the invention.

What I claim is:

1. In a closed gravity circulating system of hot water comprising a tank, hot water supply lines communicating with the tank and a plurality of plumbing fixtures, return lines from the plumbing fixtures to the tank, means comprising a pair of pipes interposed in the supply lines at a point higher than any plumbing fixture for dividing the flow of hot water into two channels, said pipes so constructed and arranged to assure constant circulation of water throughout the system.

2. An improved dual service system of hot water circulation comprising a boiler, a plumbing fixture, a supply line connecting the boiler with the plumbing fixture, a control valve interposed in the supply line, a return line between the valve and the boiler providing circulation of the water, a first radiator, a first pipe connecting the radiator to the valve, a second pipe connecting the radiator to said return line, auxiliary radiators, piping connecting the supply line and the return line respectively with the auxiliary radiators, and means operatively connected with said piping and return line for discharging air therefrom, said means including a pair of pipes so constructed and arranged as to assure constant circulation of the water throughout the system.

3. An improved dual service system of hot water circulation comprising a boiler, a plumbing fixture, a supply line connecting the boiler with the plumbing fixture, a control valve interposed in the supply line, a return line between the valve and the boiler providing circulation of the water, a first radiator, a first pipe connecting the radiator to the valve, a second pipe connecting the radiator to said return line, auxiliary radiators, piping connecting the supply line and the return line respectively with the auxiliary radiators, means operatively connected with said piping and return line for discharging air therefrom, said means including a pair of parallel pipes so constructed and arranged as to assure constant circulation of the water throughout the system.

4. An improved dual service system of hot water circulation comprising a boiler, a faucet, a supply line connecting the boiler with the faucet, a multi-way valve interposed in said line, a return line connecting the valve with the boiler to provide circulation of the water, a radiator, a pipe for leading water from the valve to the radiator, and another pipe for leading water from the radiator to the return line.

5. An improved dual service system of hot water circulation comprising a boiler, a faucet, a supply line connecting the boiler with the faucet, a multi-way valve interposed in said line, a return line connecting the valve with the boiler to provide circulation of the water, a radiator, a pipe for leading water from the valve to the radiator, another pipe for leading water from the radiator to the return line, an auxiliary radiator, a pipe connecting the supply line with the auxiliary radiator, and another pipe connecting the radiator with the return line.

6. An improved dual service system of hot water circulation comprising a boiler, a faucet, a supply line connecting the boiler with the faucet, a multi-way valve interposed in said line, a return line connecting the valve with the boiler to provide circulation of the water, a radiator, a pipe for leading water from the valve to the radiator, another pipe for leading water from the radiator to the return line, auxiliary piping connected to the supply and return lines and forming an auxiliary circuit for the circulation of water, said piping including a pair of parallel pipes to allow water from the supply line to flow simultaneously in plural paths to the return line.

7. An improved dual service system for hot water circulation comprising a boiler, a faucet, a supply line connecting the boiler with the faucet, a multi-way valve interposed in said line, a return line connecting the valve with the boiler to provide circulation of the water, a radiator, a

pipe for leading water from the valve to the radiator, another pipe for leading water from the radiator to the return line, auxiliary piping connected to the supply and return lines and forming an auxiliary circuit for the circulation of water, said piping including a pair of parallel pipes to allow water from the supply line to flow simultaneously in plural paths to the return line, and a radiator interposed in the auxiliary piping.

8. An improved dual service system for hot water circulation comprising a boiler, a faucet, a supply line connecting the boiler with the faucet, a multi-way valve interposed in said line, a re-

turn line connecting the valve with the boiler to provide circulation of the water, a radiator, a pipe for leading water from the valve to the radiator, another pipe for leading water from the radiator to the return line, auxiliary piping connected to the supply and return lines and forming an auxiliary circuit for the circulation of water, said piping including a pair of parallel pipes to allow water from the supply line to flow simultaneously in plural paths to the return line, and a faucet interposed in the auxiliary piping.

OSCAR G. WATT.
